UNITED STATES PATENT OFFICE

THOMAS SAMUEL SKILLMAN, OF ALDWYCH, LONDON, ENGLAND, ASSIGNOR TO WESTERN ELECTRIC COMPANY, INCORPORATED, A CORPORATION OF NEW YORK

SEMITAUTOMATIC TELEPHONE SYSTEM

Application filed October 15, 1930, Serial No. 488,871, and in Great Britain February 12, 1930.

This invention relates to telephone exchange systems and more particularly to such systems in which toll connections are established between central offices by means of machine switching equipment controlled over toll lines. The objects of the invention are to provide improved methods and means for enabling an operator at one office to extend a connection over a toll line to a subscriber's station in a distant office through the use of automatic switching mechanism controlled by alternating current impulses, preferably within the voice frequency range; to provide the operator with means, likewise controlled by alternating current impulses preferably within the voice frequency range, for complete supervision over such a connection and also to provide suitable circuit arrangements in a system of this nature whereby traffic may be handled in either direction over the same toll line. More specifically, the invention contemplates an improved arrangement of a two-way toll line which can be switched at either end to the local machine switching equipment in response to a signal from the other end so that a call may be set up in one direction by means of a plurality of coded voice frequency impulses designating the wanted number and transmitted over said line into a registering and controlling mechanism at the terminating office, while a call in the opposite direction may be set up by a plurality of alternating current impulses of a single frequency produced by the operation of a dialing device at an operator's position and transmitted over said line for operating automatic switches connected to the trunk line at the distant end.

While the establishment and control of telephone connections on a two-way basis over a toll line is old in the telephone art it is believed that the relatively simple and inexpensive equipment and cooperating circuits disclosed in the present invention furnishes an efficient and reliable means for establishing two-way toll connections between subscribers over toll lines.

In accordance with the invention, therefore, one specific embodiment of which is disclosed herein by way of illustration this

is accomplished in the following improved manner:

The toll trunk line terminates in a jack at an operator's position in each of the two offices which are connected by the said toll line and at each of which positions there is the usual positional equipment such as interconnecting cords, operator's telephone circuit and other apparatus well known to the art. At each end the trunk is also extended to a switching relay which responds to a connection from the distant end and serves to switch the trunk conductors from the operator's position at the incoming end to the automatic switches or to a registering and controlling mechanism which, when operated in the known manner, extend the toll line to the wanted subscriber. At each end of the trunk there is also provided a number of tuned alternating current relays connected in parallel across both sides of the trunk through a repeating coil and each responding to a single voice frequency current circuit. These relays, in turn, control a group of local direct current relays which, when operated in response to a corresponding operation of the voice frequency relay or combination of relays, cause the operation or release of other local direct current relays, which, in effect, translate the voice frequency impulses received over the toll line into the familiar two-wire direct current impulses. These impulses may be transmitted into a registering mechanism connected to the automatic switches or through a repeater directly into the automatic switches. When the impulses are recorded in a controlling mechanism, said mechanism thereafter causes the operation of the said automatic switches in the known manner to extend the toll line connection to the wanted subscriber's line.

The operator's position at one end of the trunk terminus which, for the sake of convenience is designated herein as office A, is provided with a key-set containing ten non-locking keys, each of which keys designates one of the ten digits. These keys are suitably wired to four separate sources of voice frequency currents, either separately or in combination, at each key. Common to all the

keys and responding to the operation of any of them is a relay device which, in cooperation with a common position key and circuits controlled by the cord inserted into the trunk jack, as more fully explained hereinafter, connects to the trunk line the voice frequency circuits controlled by the digit key depressed.

The voice frequency current sources which are wired to the key-set are likewise extended to a separate group of relays, independent of the key-set, to effect the transmission to the other end of the trunk for a call established in the opposite direction, of other voice frequency impulses the component frequencies of each of which correspond to a distinct supervisory signal to be transmitted to the originating end of the trunk line so that a supervisory signal is transmitted on a voice frequency impulse basis to the originating end of the trunk and there, by the voice frequency responsive relays and direct current relays responsive thereto, the impulse is translated to the correspondingly standard supervisory signal well known in the art.

The operator's position at the other end of the trunk terminus which, for the sake of convenience is herein designated as office B, is provided with a dialing device capable, when connected to the line in the well known manner, of producing line interruptions or impulses. These impulses, in combination with a dialing key at the position where the trunk terminates in office B, control local direct current circuits which effect the intermittent closure of a single voice frequency circuit to the trunk line. At office A, each voice frequency impulse causes the operation of the voice frequency relay which is tuned to respond to the voice frequency current of the impulse. A direct current relay responds to the operation of the voice frequency relay and, in combination with the operation of another direct current relay, causes the translation of the impulse into the familiar two-wire direct current impulse, which may be transmitted into the automatic switches connected to the trunk. The automatic switches respond to each translated impulse and extend the toll connection to the wanted subscriber's line. The trunk line at office B likewise contains local circuits controlling the closure of voice frequency current sources in requisite combinations for the transmission to office A of the various supervisory signals originating at office B for effective recognition at office A in a call extending from office A to office B.

In general, the system operates in the following way: When an operator at office A wishes to extend a connection to a wanted subscriber in the distant office B she takes into use the toll trunk connecting the two offices by inserting into the trunk jack at her position a toll cord which is arranged in the well known manner. She thereafter depresses the

listening key of the cord and, if the trunk is busy either because it has already been taken into use by the operator at office B for extending a call to office A or because it is in use on a previously established call, a busy tone is transmitted to the operator's telephone circuit warning her that the trunk is busy. If the trunk is idle no tone will be heard, and she will proceed thereafter to complete the call.

Before she proceeds with the function of depressing the keys designating the wanted number, however, she waits for a signal that the trunk is ready to receive the impulses to be produced by the successive operation of the various digit keys. This signal, in the present embodiment of the invention, takes the form of lighting the toll cord supervisory lamp and is the result of sending out from office A an impulse of a combination of certain voice frequency currents which effects the response of voice frequency relays at office B. This impulse at office B causes the operation of the trunk switching relay thereat, connects the trunk conductors to the local automatic switches, establishes a busy tone circuit for the operator at office B and causes the connection of a register and control mechanism to the direct current circuits controlled by the voice frequency responding relays. Thereafter, a return impulse is transmitted back to office A which results in lighting the supervisory lamp in the cord, thereby indicating to the operator at office A that the trunk is ready for key sending. The operator depresses the common position key and proceeds thereafter to depress in definite succession the digit keys representing the number of the called subscriber. With each key depressed a coded voice frequency impulse is transmitted over the line for a definite duration. These key impulses cause the response of voice frequency relays at office B which are tuned to operate on the separate voice frequency currents of which the impulse is composed and, by their operation, effect the operation or release of direct current relays which translate the received impulse into a regular two-wire direct current impulse as already mentioned. The automatic switches are then set in the well known manner and the called subscriber is rung. When the subscriber answers, a supervisory relay in the toll trunk, connected in a loop circuit with the subscriber's line is operated and its operation controls a local circuit which closes onto the trunk line a voice frequency circuit of a definite combination of voice frequency currents. The appropriate voice frequency relays at office A respond to this impulse and, in turn, control local direct current circuits which extinguish the supervisory lamp in the operator's cord circuit as an indication that the subscriber has answered. When the call is terminated, the release of the supervisory

relay effects the closure of another combination of voice frequency currents and an impulse thereof is transmitted to the originating end of the trunk, the effect of which is to light the supervisory lamp in the cord circuit as an indication to the operator that the call is over and to remove the toll cord from the trunk.

If a call is to be extended from office B to office A the operator at office B proceeds in a similar manner to take the trunk into use and likewise makes the busy test by listening for a busy tone. The designation of the called number in this case, however, is not transmitted by the depression of keys and the consequent transmission of coded impulses composed of voice frequency currents but, rather, by the operation of a dialing device which is in series with a local relay whose contacts control a group of relays one of which intermittently closes an alternating current source of a single voice frequency to the trunk. This voice frequency circuit is closed as many times as the dial is interrupted on its way to normal. The resulting voice frequency impulses cause the operation of the corresponding voice frequency relay at office A whose operation controls local circuits which affect a relay in the automatic switch connected to the trunk line so that a called subscriber's line at office "A" is reached by direct current impulses in the well known manner. The operation of the supervisory signals are, in general, controlled in the same way as those for a connection extending from office "A" to office "B" as already described.

A clearer conception of the scope and purpose of the invention may be obtained by consideration of the following description taken in connection with the attached drawings in which:

Fig. 1 shows a part of the apparatus and circuits located at one end of the trunk line connecting with an operator's position and the machine switching selectors.

Fig. 2 shows the remaining apparatus and circuits located at the same end.

Fig. 3 shows a part of the apparatus and circuits located at the distant end of said trunk line.

Fig. 4 shows the remaining parts of the apparatus and circuits at said distant end connecting with the operator's position and local automatic switches and control mechanism.

Fig. 5 shows the order in which the above mentioned drawings are to be arranged with respect to each other in order to obtain a clear understanding of the present embodiment of the invention.

Circuit operation with calls from office "A" to office "B"

We will consider first the extension of calls in one direction, say from office A, indicated

by the circuits shown in Figs. 1 and 2, to office B, indicated by the circuits shown in Figs. 3 and 4. The operator, at whose position in office A the trunk terminates in jack 114, upon receiving an order for a wanted subscriber located in office B, plugs a regular toll cord, a part of which is schematically shown in Fig. 1 into trunk jack 114. A circuit is now closed from battery on the sleeve of the cord circuit, conductor 113, relay 210 to ground. Relay 210 operates and, by opening its right contacts, opens the path of relay 213. On its left contacts it closes a battery through resistance 244 and conductor 214 to all of the windings of relays 209 and 215 and the same battery is connected in parallel by way of conductor 239 to the winding of relays 220 and 222. Relay 222 operates by a ground closure on the other side of its winding through the right back contacts of relay 221. Relay 220, however, does not operate from the ground on the back contacts of relay 209, due to the fact that, when the above mentioned resistance battery was extended to the windings of relays 209 and 215, a circuit was closed for relay 209 from the above mentioned battery through resistance 244, No. 1 winding of relay 209 to ground on the back contacts of relay 205 and also over another circuit through its No. 3 winding to ground on the back contacts of relay 207. Relay 209 operates, opens its contacts and prevents the operation of relay 220 at this time. Likewise, relay 215 operates from the same battery in parallel over a circuit through its No. 3 winding to ground on the back contacts of relay 206 and also through another circuit over its No. 1 winding to ground on the back contacts of relay 204. On its right inner contacts, relay 210 closes a circuit for slow-to-operate relay 221 by way of the top inner back contacts of relay 213, normally made contacts of relay 208, left outer contacts of relay 227, winding of relay 221 to battery. Relay 221, however, is sufficiently slow in operating so as to allow relay 222 to fully operate before the ground on its back contacts is removed. The ground at the right contacts of relay 210 is also extended through the top outer contacts of relay 213 to the winding of slow-to-operate relay 225 which also operates at this time and also, in parallel through the right outer contacts of relay 225, to the right winding of relay 216 causing this relay to operate and lock over its left winding and left inner contacts to ground on the contacts of relay 215. The operation of relay 216 closes, at its left outer contacts, a loop including coil 211, the tip and ring conductors of the cord circuit and a relay in the cord circuit through the back contacts of which is controlled the circuit of the cord supervisory lamp. The cord supervisory relay operates in this circuit and extinguishes the supervisory lamp. At its left middle con-

tacts relay 216 closes a circuit for relay 219 from battery through the winding of relay 219, left middle contacts of relay 216 to ground on the front contacts of relay 237, which relay is normally operated over its Nos. 1 and 2 windings to ground on the back contacts of relays 204 and 205 respectively. Relay 219 operates over the above circuit but performs no useful function at this time.

10 The operating path of relay 213 is controlled through the back contacts of relay 210, as already mentioned, so that if the trunk is seized at the distant office "B" for a call in the opposite direction, it will no longer be effective, as more fully described hereinafter, once the trunk has been plugged into at office "A" and relay 210 operated. Relay 225 operates over the above traced circuit to its winding from ground on the contacts of relay 210 and, on its left inner front contacts, closes one step of the circuit from voice frequency current source "Z" to the primary winding P of repeating coil 229; the final closing step being controlled through the right outer contacts of relay 224 when it is operated as described hereinafter. The secondary winding S of repeating coil 229 is connected to the normally open contacts of relay 240 whose armatures are connected to outgoing trunk conductors 233 and 234.

15 Relay 221, when operated as described above, closes a circuit from ground on its right front contacts, contacts of relay 222, which relay, it will be remembered, is slow release, winding of relay 224 to battery, causing relay 224 to operate. Relay 221 also operates relay 226 over an obvious circuit and the operation of this latter relay causes the operation of relay 228 by extending ground on its right contacts through the right inner contacts of relay 225 to the winding of relay 228. When relay 224 operates, it closes a circuit for relay 240 from ground on its left inner contacts, winding of relay 240 to battery.

20 When relay 240 operates it connects trunk line conductors 233 and 234 to the secondary winding S of repeating coil 229. Relay 224 also closes its right inner contacts to one side of the primary winding P of repeating coil 229, placing voice frequency current source W in parallel with voice frequency current source Z, which is also connected to the same side of the primary winding P of repeating coil 229 by way of the right outer contacts of relay 224. The right side of the said primary winding of the repeating coil is permanently connected to the common return circuit C of all voice frequency current sources. A calling signal impulse, therefore, consisting of combined frequencies W and Z is impressed over the primary P, repeated through the secondary S of repeating coil 229 and transmitted over the trunk line conductors 233 and 234 to the distant office B.

25 The duration of this impulse is determined by the releasing time of slow-to-release relay 222 whose circuit is opened by the operation of relay 221. The release of relay 222 causes the release of relay 224, in turn cutting off the circuits of voice frequency sources W and Z to the primary winding of the repeating coil. The calling impulse circuit above described is traced through conductors 233 and 234, top and bottom back contacts of relay 300, top and bottom primary windings P_1 and P_2 of repeating coil 301 through both left windings in series of repeating coil 316. The impulse is repeated through both secondary windings S_1 and S_2 of repeating coil 301 over a circuit including the said secondary windings and voice frequency responding relays 302, 303, 304 and 305 connected in parallel between both of the said secondary windings in series. This calling impulse operates relays 302 and 305, the former responding to voice frequency W and the latter to voice frequency Z. The operation of relay 302 opens the short circuit around the left winding of relay 306, causing this relay to operate over both of its winding in series. The operation of relay 306 opens the normal circuits of winding No. 1 of relays 311 and 312 respectively. Likewise, the operation of relay 305 removes the short circuit around the left winding of relay 309, causing it to operate over both windings in series and open the circuit of winding No. 4 of relay 312. Now relay 312 is normally operated by the circuits over the two windings mentioned above and will, therefore, release when these circuits are opened, but relay 311, which is likewise normally operated, remains operated over its No. 2 winding to ground on the back contacts of relay 307. The release of relay 312 closes a ground on its left contacts, right winding of relay 315 to battery, causes relay 315 to operate thereby and, on its right contacts, relay 312 closes ground on conductor 330, top winding of relay 400 to battery. Relay 400 operates over this circuit. Relay 315 closes battery through resistance 340 over its left outer contacts conductor 341, to the windings of relay 310 and to the winding of relays 322, 323 and 327. As soon as this battery supply is available at the windings of relays 310, it will operate in a circuit over its No. 3 winding to ground on the back contacts of relay 308 and through its No. 4 winding to ground on the front contacts of relay 309, which relay is operated over the calling impulse circuit from office A. Relay 310, on operating, closes a circuit over its contact and left inner contacts of relay 315 to the locking winding of this relay. It also extends the ground on its contacts over conductor 331, bottom No. 1 contacts and lower winding of relay 400 to battery thereby locking this relay. The operation of relay 400 connects a busy tone source BT over a path from one side of the secondary of said busy tone source BT, top No. 4 contacts of relay 130

30 70 80 85 90 95 100 105 110 115 120 125 130

400, conductor 418, normally made contacts of key 430 to the top contacts of key 428 and from the other side of the secondary of busy tone source BT, top No. 3 contacts of relay 5 400, conductor 419 to the bottom inner contacts of key 428. When key 428 is operated for the purpose described hereinafter and relay 431 is operated thereby over an obvious 10 circuit, this busy tone circuit is completed over the above mentioned contacts of key 428, condensers 426 and 432, contacts of relay 431 to the operator's telephone circuit OT which is not shown. When, therefore, the operator 15 at office B desires to take the trunk into use for extending a connection in the opposite direction to office A and this trunk has already been appropriated by the operator at office A to extend a connection to office B, the operator at office B, in order to 20 ascertain whether or not the trunk is busy, operates key 428 of the trunk. The operation of the key operates relay 431 and connects the operator's telephone circuit OT to the busy tone source BT over the afore-traced 25 circuit. The busy tone circuit will be applied in the well known manner to the operator's receiver and indicates to her that the trunk is busy. If, on the other hand, the trunk is 30 idle at the time that the operator at office B makes the busy test by operating key 428, relay 400 will be normal, the busy tone circuit is not closed and the operator will receive no tone, indicating thereby that the 35 trunk is free and available.

35 Relay 400, on operating, switches the trunk conductors 342 and 343 over the top and bottom No. 2 front contacts to conductors 424 and 425, respectively, connecting with the local automatic selector indicated schematically in Fig. 4.

When the calling impulse above described is terminated relays 222, 224, 226, 227 and 45 240 release at office A and relays 302 and 305 release at office B, in turn short-circuiting the 50 left windings of relays 306 and 309, respectively, causing these latter relays to release. Relay 312 re-energizes over its No. 1 and No. 4 windings due to the release of relays 306 and 309, and ground is connected to conductor 55 414 by way of the left front contacts of relay 312, conductor 332, bottom No. 3 contacts of relay 400, right contacts of relay 412 to conductor 414. This ground is for the purpose of initiating the operation of the register and control mechanism connected or controlled over this conductor in order that the 60 said mechanism becomes connected to the calling trunk and local selector. The register and control mechanism above mentioned is neither shown nor described herein as it forms no part of the present invention and the connection between the calling trunk, the local switching selector and the control mechanism may be brought about in any suitable 65 manner.

When the register and control mechanism is ready for operation as a result of the initial ground on conductor 414, a ground is received back on conductor 413 which will operate relay 411 over its right winding and the same ground is passed through the right inner contacts of this relay, conductor 433, to the left winding of relay 326. Relay 411 is made slow to operate and relay 326 slow to release so as to give relay 326 sufficient time to operate before its energizing circuit is cut off at the contacts of relay 411 by the operation of this latter relay, and relay 326 is prevented from releasing immediately when this circuit is opened due to its slow releasing qualities. Relay 411, at its left inner contacts, locks over its left winding to ground on conductor 331 and, at its left outer contacts, closes a circuit for relay 404 from ground on conductor 414 thereby causing relay 404 70 to operate and close through conductors 334, 335, 336 and 337 to the register and control mechanism connected to the contact banks to which the other side of these conductors are extended. Relay 326 closes a circuit for 75 relay 324 from ground on the left back contacts of relay 329, left contacts of relay 326, winding of relay 324, resistance 317 to battery. Relay 324 energizes and, at its left contacts, closes the circuits from voice frequency current sources, W and Y, conductor 333, to the primary winding P of repeating oil 320, the other side of which primary winding is permanently connected to the common return C of the voice frequency 80 sources. Relay 324 also closes an obvious circuit from its right inner contacts to the top winding of relay 300, causing this relay to operate and switch the trunk conductors 85 233 and 234 to the secondary winding of repeating coil 320. As soon as the voice frequency circuits W and Y are closed, an impulse of these combined frequencies is, therefore, sent out over the trunk to office A. This 90 impulse circuit is traced from the secondary winding S of repeating coil 320, top and bottom front contacts of relay 300, conductors 233 and 234, top and bottom back contacts of relay 240, top and bottom primary windings P_1 and P_2 of repeating coil 232, top middle back contacts and bottom No. 2 back contacts of relay 213, condensers 245 and 246, winding of relay 212 and condenser 247 which close the trunk 95 loop. This impulse is repeated over a circuit including the secondary windings S_1 and S_2 of repeating coil 232 and voice frequency 100 relays 200, 201, 202 and 203 connected in parallel between both of said secondary windings. The impulse WY energizes voice frequency relays 200 and 202. Relay 200 opens its contacts, removing the short circuit around the right winding of relay 204 and causes this relay to operate over both its 105 windings in series, while relay 202 in a simi- 110 115 120 125 130

lar manner, causes the operation of relay 206. The operation of relays 204 and 206 opens the energizing circuits of relay 215 through its Nos. 1 and 3 windings, respectively, and causes it to release. The release of relay 215 unlocks relay 216 which, it will be recalled, had energized over the right outer back contacts of relay 225 when the trunk was first plugged into at office A and locked to the contacts of relay 215. The release of relay 216 opens an aforetraced loop to the cord circuit, releases the supervisory relay therein and causes thereby the lighting of the cord supervisory lamp. This indicates to the operator at office A that the trunk is ready for the transmission of key impulses. At the termination of the above described impulse from office B, relays 200 and 202 release causing, in turn, the release of relays 204 and 206 and the consequent reoperation of relay 215.

The operator, to perform this function, depresses key 100, which is individual to the trunk, and thereafter depresses in succession the digit keys of key-set 119 in the order corresponding to the wanted number at office B. Each depression of the key sends an impulse of voice frequency current over the trunk. The duration of each impulse, however, is not regulated by the length of time the operator keeps the digit key depressed but by the operating time of relays 118 and 117. Whenever a digit key is depressed, say for example, digit key 3, a circuit is closed from ground on conductor 120, right contacts of key 3, winding of relay 118 to battery. Relay 118 operates and, on its right outer contacts, closes an obvious circuit for slow-operate relay 117 and, on its left contacts and through the outer contacts of relay 117, closes one side of the primary winding of repeating coil 116 to conductor 102 of the voice-frequency sources common return circuit, while the other side of the primary of repeating coil 116 is closed over the right inner contacts of relay 118 and inner contacts of relay 117 to the left contacts of the individual keys of key-set 119. Relay 117, however, is slow to operate and its time characteristics may be regulated in the well known manner to suit the desired duration of the impulse. When it operates, after a time interval, the impulse current is cut off, even though the operator may still have key 3 depressed. The duration of the impulse, therefore, is regulated by the operating time of relay 117 no matter how long the digit key is kept down. Now the voice frequency code for the digit 3 impulse is WX so that a circuit from these two separate voice frequency sources is closed over conductors 101 and 103 to the left contacts of key 3 and from thence through the right contacts of relay 118, inner contacts of relay 117, primary winding of repeating coil 116, outer contacts of relay 117, left contacts of relay 118 to the return completing circuit on conductor 102.

This combination of voice frequency currents is then repeated in the secondary windings of the repeating coil 116, the circuit being carried through the contacts of key 100, top middle back contacts and bottom No. 2 back contacts of relay 213, trunk conductors 230 and 231, primary windings P_1 and P_2 of repeating coil 232, back contacts of relay 240, trunk conductors 233 and 234, back contacts of relay 300, primary windings P_1 and P_2 of repeating coil 301, left windings of repeating coil 316. The impulse is then repeated through the secondary windings S_1 and S_2 of repeating coil 301 to the voice frequency relays 302, 303, 304 and 305. The impulse consisting of voice frequency currents W and X causes the operation of relays 302 and 303. It will be noted that the voice frequency relays 200, 201, 202 and 203 at office A are connected to the secondary windings S_1 and S_2 of repeating coil 232, through the primary windings of which passes the impulse current above described. Although the impulse is repeated through secondary windings S_1 and S_2 of repeating coil 301 at office B, causing thereby the response of the proper voice frequency relays, a similar repetition of the impulse current into the secondary windings S_1 and S_2 of repeating coil 232 at office A cannot take place due to the fact that the secondary windings of the latter repeating coil are connected to the drop side of the associated primary windings and, consequently, a part of the current traversing the primary winding will traverse the associated secondary winding differentially, the operation being the same through both sets of windings, thereby reducing to a negligible quantity the induced voltage between the two secondary windings and the corresponding flow of current through these windings and the voice frequency relays connected between them. On the other hand, the secondary windings S_1 and S_2 of the repeating coil 301 at office B are connected to the high potential side of the line with respect to an incoming signal and, consequently, the impulse current divides between the primary winding P_1 and the associated secondary winding S_1 so that the current through the secondary winding has an aiding effect, thereby increasing the induced voltage between the two secondary windings and the corresponding flow of current through these windings and the voice frequency relays connected between them. It is thus seen that for a key impulse transmitted from office A to office B the impulse current is differential with respect to the secondary windings of the repeating coil on the near side of the line and aiding with respect to the secondary windings of the repeating coil on the far side of the line. Although key impulses are not transmitted in the opposite direction when establishing a call from office B to office A as described hereinafter, an inspec-

tion of the drawings will make it clear that the same thing would be true with respect to an impulse in such a direction if it should be thought advisable to modify the present embodiment of the invention to send key impulses in both directions.

The operation of relays 302 and 303 causes the operation of direct current relays 306 and 307 in the described manner. Relay 306 connects ground to conductor 334 and effects thereby the closure of a circuit in the register and control mechanism of that component of the impulse as is represented by voice frequency current W. In a like manner relay 307 grounds conductor 335 to register in the control mechanism that component of the impulse as is represented by voice frequency current X.

It will be observed that the operation of relays 306 and 307 does not result in a disturbance of the circuits controlled by relays 310, 311 and 312 due to the fact that, in some cases, the holding circuits of these relays are not disturbed while in others, although the holding circuits are open, yet the relays are sufficiently slow in releasing so as to hold up during the impulse intervals between the successive depression of digit keys at office A. When the impulse is terminated relays 302 and 303 release, in turn releasing relays 306 and 307 and removing ground from conductors 334 and 335. Each succeeding impulse resulting from the depression of any of the individual keys of key-set 119 results in the operation of one or more relays 302, 303, 304 and 305 with a corresponding grounding of one or more of the conductors 334, 335, 336 and 337 for the registration of the various components of the transmitted impulses in the register and control mechanism. When all of the impulses have been thus transmitted and recorded, the automatic equipment functions in the well known manner to extend the line through to the called subscriber's line in the local automatic office and to cause his bell to be rung. When the called subscriber answers, battery is connected by the selector switch to conductor 424, top No. 2, front contacts of relay 400, conductor 342, winding 318 of repeating coil 316, conductor 338, winding of relay 403 to ground. Relay 403 operates and, in turn, operates slow-release relay 402. Relay 402, at its right outer contacts, closes ground to operate slow-operate relay 329 by way of conductor 435, normally made contacts of relay 313, right outer contacts of relay 324, winding of relay 329 to battery. Before relay 329 operates, however, relay 402 has closed a circuit from battery through resistance 436, conductor 339, to the winding of slow-release relay 327, which relay operates to ground on the left back contacts of relay 329 before this relay operates. When relay 329 operates, a circuit is closed for relay 325 from

battery through the winding of relay 325, contacts of relay 327, left front contacts of relay 329. Relay 325 operates and closes an obvious circuit for relay 300 over its top winding. Relay 325 also closes through the circuits from voice frequency sources W and X to the primary winding P of repeating coil 320 so that an impulse of combination voice frequency current WX is transmitted over the trunk by way of trunk conductors 233 and 234 to office A over the trunk loop previously traced. Since relay 329 in energizing also opens the circuit of relay 327, the releasing time of this relay determines the duration of the impulse transmitted. This impulse causes the operation of relays 200 and 201 at office A and relay 237, which is normally energized over windings 1 and 2 is caused to release by the operation of relays 200 and 201 and the resulting operation of relays 204 and 205. Relay 237, by releasing, operates relay 216 over its right winding, which relay locks over its left winding and left inner contacts to ground on the front contacts of relay 215. Relay 216, over its left outer contacts, closes an aforementioned loop to the cord circuit through the retardation coil 211 and thereby causes the extinguishing of the supervisory lamp in the cord circuit as an indication that the subscriber has answered, which signal is maintained as long as the conversation continues as no circuit exists to unlock relays 215 and 216, the former relay holding over its No. 1 and 3 windings to ground on the back contacts of relay 204 and 206 at the termination of the answering impulse.

At the conclusion of the conversation the called subscriber restores his receiver, opening thereby the subscriber's loop and causing the release of relays 403, 402 and 329. Relay 329 on closing its back contacts operates relay 324 over a circuit from battery through resistance 317, winding 324, left contacts of relay 326, which relay is slow release and was operated over its right winding to ground on the left front contacts of relay 329, back contacts of relay 329 to ground, so that an impulse of the combination voice frequency WY is transmitted over the trunk during the time that relay 324 is operated. When relay 326 releases, relay 324 likewise releases and the impulse is terminated. Since relay 400 is still energized, relay 328 is ineffective in prolonging this impulse beyond the time controlled by the release of relay 326. At office A this impulse causes the operation of relays 200 and 202, thereby operating relays 204 and 206 and releasing relay 215 which, in turn, releases relay 216. Relay 216 opens the loop to the cord circuit and causes the lighting of the supervisory signal therein. At the termination of the impulse relay 215 reoperates over its No. 1 and 3 windings from ground on the back con-

tacts of relays 204 and 206, respectively, to battery through resistance 244 on the left contacts of relay 210. The operator now withdraws the plug of the cord circuit from the trunk jack 114 opening thereby the circuits of relays 210, 225 and 215. The release of relay 210 opens the circuit of relay 221 which also releases. The release of relay 221 opens the circuit of relay 226 and the release of relay 225 opens the circuit of relay 228. Both of these relays are slow release and, during the interval in which they are held in an operated position, a circuit is closed to energize relay 227 from ground on the back contacts of relay 221, left contacts of relay 226 or right contacts of relay 228, winding of relay 227 to battery. Relay 227 will thus operate and remain operated until relays 226 and 228 have released, each of whose separate circuits depends on the release of relays 221 and 225 respectively. The circuit of relay 221 is opened as soon as relay 227 breaks its left back contacts and that of relay 225 on the releasing of relay 210 which, as already pointed out, releases as soon as the operator withdraws the plug from the trunk jack. Relay 227 operates relay 240 over an obvious circuit and also closes the circuit from voice frequency sources W and Y to the primary winding P of repeating coil 229. An impulse of current of these two frequencies is now transmitted over the trunk to office "B" in the described manner and causes thereat the operation of relays 302 and 304. The operation of these relays operates relays 306 and 308 and they, in turn, release relay 310. Relay 310 releases relays 315, 411, 412 and 400. Relay 315 releases relay 327. The circuits of relays 310, 323 and 322 are likewise opened by the release of relay 315 so that only relays 311 and 312 remain normally energized at the termination of the impulse and thus restore the trunk to normal.

If the called subscriber is found busy, a busy flash signal will be received over the automatic selectors by way of conductor 424 and will alternately operate and release relay 403 which, in turn, will alternately operate and release relay 402. Relay 402 will alternately operate and release relay 329 and relay 329 will alternately operate and release relay 327 over a circuit from ground on the left back contacts of relay 329, winding of relay 327, to battery through resistance 340 on the left outer contacts of relay 315, which relay remains locked to the contacts of relay 310 if the release signal as above described is not transmitted from office A as it would not be in the case when the subscriber does not answer. Relay 327 operates relay 325 from ground on the left front contacts of relay 329, contacts of relay 327, winding of relay 325 to battery, and the same ground on the left front contacts of relay 329 is extended in a parallel circuit to the right wind-

ing of relay 326 causing this relay to operate and release simultaneously with relay 327. Relay 326, on its left contacts, closes a circuit from battery through resistance 317, winding of relay 324, left contacts of relay 326 to ground on the left back contacts of relay 329. Consequently when relay 329 releases, relay 326, being slow release, the above traced circuit for relay 324 becomes effective thereby causing this relay to operate. Thus it is seen that relay 325 operates when relay 329 is operated and relay 324 operates when relay 329 is released. This causes alternate combination circuits to sources WX and WY respectively to be closed and the corresponding impulses transmitted over the trunk. The impulse WX operates relays 200 and 201 at office A causing the corresponding operation of relays 204 and 205 respectively. Relay 204, at its back contacts, opens the circuit to the No. 1 winding of relay 237, and relay 205, at its back contacts, opens the No. 2 winding of this relay. Relay 237 releases and, at its back contacts, closes an aforetraced circuit to the right winding of relay 216 which, when operated, locks over its left winding and left inner contacts to ground on the contacts of relay 215, which latter relay remains operated over its No. 3 winding from the back contacts of relay 206 and battery through resistance 244 on the left contacts of relay 210. Relay 216 closes, on its left outer contacts, the loop including coil 211 to the cord circuit, operating the supervisory relay therein and extinguishing thereby the cord supervisory signal.

When the impulse consisting of frequencies WX has terminated and that of frequencies WY immediately follows, relay 200 remains operated but relay 201 releases and relay 202 operates. In consequence relay 205 releases and relay 206 operates. The operation of relay 206 opens the remaining operating circuit over the No. 3 windings of relay 215 causing this relay to release and open the locking circuit of relay 216 which relay thereafter releases. Relay 216 at its left outer contacts opens the aforementioned loop to the cord, releases the supervisory relay therein and thereby causing the relighting of the supervisory signal. Thus the alternate transmission of voice frequency impulses WX and WY, when the called subscriber is busy, causes the flashing of the supervisory lamp in the cord circuit at office "A" as an indication of this fact.

If, when the called subscriber is busy, the operator at office "A" wishes to offer the call to the operator at the distant office "B", she may do so by ringing over the trunk. The ringing equipment is so arranged that a voice frequency current impulse is sent out which operates a set of relays to extend the call to a manual position and from which point the call is then completed in the well known man-

- ner. The ringing current is applied from the cord circuit in the well known manner and energizes relay 212 which, in turn, energizes relay 223 over an obvious circuit. Relay 223 closes the circuits of voice frequency sources XZ on the trunk line. At office "B" relays 303 and 305 are operated by the voice frequency combination and they, in turn, operate relays 307 and 309 to open the circuits to the 5 Nos. 2 and 4 windings of relay 314 thereby causing it to release. Relay 314 operates relay 410 over an obvious circuit which locks over its right contacts to ground on conductor 331 to the contacts of relay 310. Relay 410 10 closes ground on its left front contacts to conductor 415 which leads to a special service operator's position. The auxiliary operator then extends the call in the well known manner; supervision being received back by way 15 of conductors 416, 424 and relay 403. When the call is terminated and the called subscriber restores, the restoration of the trunk to its normal position takes place in the manner already described. 20
- 25 *Circuit operation with calls from office "B" to office "A"*

When the operator at the outgoing position of office "B" inserts the plug of the calling cord into trunk jack 405, relay 406 operates from a battery circuit extending from the sleeve of the cord, sleeve of jack 405, winding of relay 406 to ground. The operation of relay 406 closes a circuit for relay 403 from ground through the winding of relay 403, conductor 338, winding 318 of repeating coil 316, conductor 342, top No. 2 back contacts of relay 400, normally made contacts of key 430, winding 421 of repeating coil 422, contacts of relay 406, winding of retard coil 429 to battery. Relay 403 operates and, in turn, operates relay 402. A previously described circuit is now closed for relay 329 from ground on the right outer contacts of relay 402, causing this relay to operate. The operation of relay 402 likewise closes, on its right inner contacts an aforetraced circuit from battery through resistance 436 to the winding of relay 327 which operates from ground on the 30 back contacts of relay 329 before this relay has broken its back contacts. When relay 329 operates, a previously described circuit through the contacts of relay 327 is closed for relay 325 and this relay now closes, on its right contacts, the circuit to the top winding of relay 300. It also closes on its left contacts the circuits from the voice frequency sources W and X to the primary P of the repeating coil 320. A voice frequency impulse of the 35 combination WX is now transmitted over the trunk line in the manner already described in connection with the establishment of a call in the opposite direction to the one now under consideration.

65 At office "A" this impulse causes the oper-

ation of relays 200 and 201, the operation of relays 204 and 205, the consequent release of relay 237 and the operation of relay 216 in the manner described. When relay 216 operates it closes battery through resistance 241 on its right inner contacts to all the windings of relays 209 and 215 and to the windings of relays 220 and 222. Relay 209 operates over its No. 3 winding to ground on the back contacts of relay 207 and relay 215 operates over its No. 3 winding to the back contacts of relays 206 and No. 2 winding to the front contacts of relay 205. The operation of relay 215 closes a locking circuit for relay 216 from ground on its front contacts, left inner contacts of relay 216, left winding, to battery. Relay 222 also operates from ground, on the right back contacts of relay 221. At the end of the impulse, relay 237 reoperates, relays 215 and 209 remain operated and relay 216 remains locked. Relay 219 now operates in a circuit from battery through its winding, left middle contacts of relay 216 to ground on the front contacts of relay 237. Relay 213 also operates from ground on the right outer contacts of relay 216, right outer contacts of relay 210, winding of relay 213 to battery. Relay 213 locks to the operating ground independent of relay 210. The operation of relay 213 connects both sides of the secondary of the busy tone circuit over its bottom No. 3 and 4 contacts to the trunk conductors 235 and 236 so that, if the operator at office "A" endeavors to seize the trunk at this time, a circuit can be completed over the trunk conductors through the cord to her telephone circuit substantially in the same manner as already described for operator "B" to apprise her of the fact that the trunk is in use. Relay 213 also 40 switches the trunk conductors 230 and 231 by way of the top middle front and bottom No. 2 front contacts to the conductors 217 and 218 connecting with the two windings 112 and 111 respectively of repeating coil 121 and the automatic repeater of the local switching selectors. Relay 219, over its right contacts, closes a circuit for relay 105 in the automatic repeater from battery through the winding of relay 105, conductor 115, left outer contacts of relay 225, right back contacts of relay 220, right contacts of relay 219 to ground on the back contacts of relay 204. Relay 219 also connects battery through resistance 242 and left contacts to the windings of relay 238 which, however, does not operate at this time. Relay 105, on its left contacts, closes an obvious circuit for relay 104 which operates and, on its right contacts, closes the ring conductor 125 preparatory to the receipt of the repeated dial impulses as described hereinafter. Relay 104 connects ground to conductor 122 and to one side of the right winding of relay 110.

Since the automatic equipment at office A 45

is arranged so that as soon as the trunk conductors are switched to the automatic selectors no further delay is necessary to wait the attachment of a recording mechanism 5 for the reception of dial impulses, there is no need for supplying the operator at office B with a dial signal as was the case in the extension of a call in the opposite direction from office A to office B, where a register and 10 control mechanism has to be connected to the trunk before the incoming impulses can be stored. The operator at office B does not wait for a dial signal after the trunk has been seized and has made a busy test therefor but 15 proceeds to dial the wanted number without any further delay.

The operator at office B prepares to dial by operating dialing key 430 and thereafter operating the dialing device 408. The operation 20 of key 430 transfers the circuit of relay 403 from battery through coil 429 to battery through the contacts of the dialing device 408 and resistance 409. On the return of the dial, relay 403 releases for each impulse and, on 25 the first impulse, closes a circuit from ground on its back contacts, bottom No. 4 contacts of relay 400, conductor 437, windings of relay 322 and 323 in parallel, left outer contacts of relay 315, resistance 340 to battery. The 30 ground side of this circuit also extends from the windings of relays 322 and 323 to the bottom winding of relay 300. Relays 322, 323 and 300 operate. Relay 322 is slow to release and does not release during the impulsive period. Neither does relay 300. Relay 323, 35 however, operates for each break period of the dial and closes through the circuit of voice frequency W to the primary winding P of repeating coil 320. At the distant end, this 40 causes the operation of relays 200 and 204 in the described manner. The operation of relay 204 opens the afore-traced operating circuit of relay 105 of the automatic repeater, the circuit reclosing again at the end of the 45 impulse. Relay 105 on closing its left back contacts closes a ground through the left contacts of slow-releasing relay 104 to the winding of relay 106. Relay 106 operates, short-circuits the trunk conductors at its 50 left contacts and at its right contacts closes a circuit for relay 107 from ground on the right contacts of relay 104, which locks to operating ground. Relay 107, in turn, closes a circuit for relay 109 which operates, but performs no function at this time. As the 55 impulses are transmitted, relay 105 alternately releases and operates, thereby opening and closing the trunk loop conductors to the automatic selector, causing it to step in the known manner and connect to another selector of the successive switching stage or to the final connector. Thus for each impulse produced by the dial 408 there corresponds an impulse 60 for relay 105. In this way the successive operation and release of relay 105 causes the 65

proper setting of the automatic equipment connected to the repeater shown in Fig. 1 in the well known manner.

When the pulsing is terminated and the called subscriber's line is reached, relay 105 70 reoperates, relay 106 releases and both windings of relay 110, in series with relay 108, are connected across the trunk conductors extending to the calling subscriber's line in the following circuit: battery through the left 75 winding of relay 110, winding of relay 108, winding 123 of repeating coil 121, conductor 125, right contacts of relay 105, the extension of the ring conductor through the train of selectors, subscriber's loop, tip conductor 80 through the train of selectors, conductor 126, winding 124 of repeating coil 121, right winding of relay 110, conductor 122 to ground on the right contacts of relay 104.

When the called subscriber answers, relay 85 110 is operated over the above-traced loop and this relay closes ground on its contacts, conductor 127, left back contacts of relay 220, conductor 243, top inner front contacts of relay 213, normally made contacts of relay 208, left back contacts of relay 227, winding of relay 221 to battery. Relay 221 operates and, at its right front contacts, closes a circuit for relays 224 and 226. Relay 224 90 operates under the control of relay 222 and which, in turn, has its circuit opened when relay 221 operates. Relay 226 operates but performs no useful function at this time. Since relay 225 is now not energized, relay 224 sends out an impulse consisting of voice frequency combination WX and not WZ, thereby causing the operation of relays 302 and 303 and the consequent release of relay 311 at office B in the described manner. Relay 311 operates relay 315 over its right winding and this latter relay closes a circuit from battery through retard coil 321, right contacts of relay 315, winding 319 of repeating coil 316, conductor 343, bottom No. 2 contacts of relay 400, trunk conductor 419, winding 423 of repeating coil 422, winding of relay 407 to ground. The operation of relay 407 establishes a loop over the cord in series with supervisory relay therein which operates and extinguishes the supervisory lamp in the cord circuit as an indication that the called subscriber has answered. 105

At the conclusion of the call the subscriber at office A restores his receiver, thereby releasing relay 110 which, on opening its contacts, releases relay 221. Relay 221 operates relay 227 by way of the left contacts of relay 226, thereby causing the closure and transmission of a voice frequency impulse WY to office B. Relays 302, 304, 306, and 308 110 operate as a result of this impulse, thereby opening the circuit of relay 310 which then releases. Relay 315 now releases and opens the circuit of relay 407, causing thereby the lighting of the supervisory lamp in the cord 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955

circuit as an indication to the operator that the call is terminated and that she may remove the cord from the trunk. When the cord is removed, relays 403 and 402 release, thereby releasing relays 329, 322, 310 and 327. Relay 329 operates relay 324 in the described manner through the left contacts of relay 326 and closes voice frequency combination WY to office A. The duration of this impulse is governed by relays 324, 328, and 326 as previously described. The impulse WY causes the operation of relays 200, 202, 204 and 206 at office A with the consequent release of relay 215 and the unlocking of relay 216 as well as the release of relays 222, and 213, thereby restoring the trunk to normal at office A.

If the subscriber is found to be busy, a busy flash is transmitted over the subscriber's loop to supervisory relay 110 which, on operating, intermittently operates relay 221 over the afore-traced circuit. Relay 221 will, by the successive operation and release of relays 224 and 227 in the described manner transmit back over the trunk voice frequency impulses WX and WY alternately. Impulse WX causes the operation of relays 302 and 303, the operation of relays 306 and 307 the consequent release of relay 311 and the operation of relay 315. Relay 315 closes an aforetraced circuit for relay 407 which extinguishes the cord supervisory signal as already described. Impulse WY causes the operation of relays 302 and 304, the operation of relays 306 and 308, the release of relay 310, the release of relay 315, the consequent release of relay 407 and the lighting of the cord supervisory lamp as already described. Thus relay 315, by operating and releasing in response to the two voice frequency signals, operates and releases relay 407 and, in turn, flashes the cord supervisory lamp in accordance with the busy signal.

Circuit seized at both ends

If the trunk circuit is seized at both ends, then the insertion of a cord in trunk jack 114 at office A will cause the operation of relay 210 as already described while the insertion of a cord in trunk jack 405 at office B will cause the operation of relay 216 as already described. Thus, a race will take place between the operation of relay 210 and relay 216. If relay 210 should operate first and break its right back contacts, then the operation of relay 216 will not be effective for operating relay 213 since the operating circuit for this relay is controlled from ground on the right outer contacts of relay 216 and the right outer back contacts of relay 210. Under such circumstances a circuit is closed for relay 225 from ground on the right inner contacts of relay 210, top outer contacts of relay 213, winding of relay 225 to battery. A circuit is now closed for relay 221 from

battery through the winding of relay 221, left outer contacts of relay 227, normally made contacts of relay 208, top inner back contacts of relay 213, right inner contacts of relay 210, to ground. Relay 221 operates relay 226 and relay 226 closes a circuit for relay 228 from ground on its right contacts, right inner front contacts of relay 225, winding of relay 228, to battery. The operation of relay 228 closes a previously described circuit for relay 224 and this relay causes an impulse of current of voice frequency combination WZ to be transmitted over the trunk line to office B where the impulse causes the operation of relays 302 and 305 and the consequent release of relay 312 in the manner described.

A circuit is now closed for relay 400 from battery through its top winding, conductor 330, to ground on the right contacts of relay 312. The operation of relay 400 closes the circuit from busy tone source BT transmitting busy tone to the operator's telephone circuit to indicate to the operator at office B that the trunk has been taken into use at the other end. Relays 403 and 402 will have been operated, however, prior to the operation of relay 400 over a previously described circuit with coil 429 in series with relay 403. This circuit, however, is interrupted by the operation of relay 400 thereby preventing the backward transmission of an impulse of voice frequency combination WY by the consequent energization of relay 324. This is prevented by relay 401 which short-circuits relay 324 over its front contacts for a time which is long enough to prevent relay 324 from sending a complete signal. This circuit is not effective when relay 411 is energized so that no interference will be occasioned when relays 403 and 402 release as a result of the subscriber restoring. If either operator plugs in at any later stage of the call she will receive busy tone in the manner already described.

In case the operator at office A seizes the trunk on a connection established at office B and during the time that the release signal is being transmitted thereto, the insertion of the cord will not disturb the complete transmission of the release signal since the ground on the contacts of relay 210 cannot be effective to operate relay 221 until relay 227 has released, which latter relay, as previously noted, controls the duration and transmission of the release signal to office B. Likewise, in case the operator at office B seizes the trunk for the establishment of another call when a connection already exists from a set-up in the opposite direction and during the time that a release signal is being transmitted to office A as a result of the release of relay 403, the insertion of the cord plug in jack 405 will not result in a shortening of the releasing impulse as the slow releasing characteristic of relay 401 maintains this relay oper-

ated for the proper interval and, in turn, prevents the operation of relay 324 which is necessary for the transmission of the impulse for preparing the distant end of the trunk for the reception of dial impulses.

5. What is claimed is:

1. In a telephone exchange system comprising a first and second telephone office, a two-way trunk line interconnecting said offices, a plurality of alternating current sources of different frequencies in each of said offices, means at said first office for selectively applying said plurality of alternating current sources to said trunk line to produce coded alternating current impulses thereover, means at said second office for applying one of said plurality of alternating current sources over said trunk line to produce alternating current impulses of a single frequency thereover, means responsive to the appropriation of said trunk line at said first office for setting up a connection at said second office by the said coded alternating current impulses, and means responsive to the appropriation of said trunk line at said second office for setting up a connection at said first office by the said alternating current impulses of a single frequency.

2. In a telephone exchange system comprising a first and second office, a two-way trunk line interconnecting said offices, a plurality of alternating current sources of different frequencies in each of said offices, means at said first office for selectively applying said plurality of alternating current sources to said trunk line to produce coded alternating impulses thereover, means at said second office for applying one of said plurality of alternating current sources over said trunk line to produce alternating current impulses of a single frequency thereover, a register and controlling mechanism at said second office, means for connecting said register and controlling mechanism to said trunk line, means in said trunk line at said second office responsive to said coded alternating current impulses, and means controlled by said responsive means for transmitting said impulses to said register and controlling mechanism.

3. A telephone exchange system comprising a first and second office, a two-way trunk line interconnecting said offices, a plurality of alternating current sources of different frequencies in each of said offices, means in said first office for selectively applying said plurality of alternating current sources to said trunk line to produce coded alternating current impulses thereover, means at said second office for applying one of said plurality of alternating current sources to said trunk line to produce alternating current impulses of a single frequency thereover, a register and controlling mechanism at said second office, means for connecting said regis-

ter and controlling mechanism to said trunk line, automatic switches at said first office, means for extending said trunk line to said automatic switches at said first office, means in said trunk line at said second office responsive to said coded alternating current impulses for transmitting said impulses to said register and controlling mechanism when a connection is extended in one direction, and means in said trunk line at said first office responsive to alternating current impulses of a single frequency for operating said automatic switches when a connection is extended in the opposite direction.

4. A telephone exchange system comprising two telephone offices and a two-way interconnecting trunk line with means for extending a connection in one direction by coded alternating current voice frequency impulses transmitted thereover and for extending a connection in the opposite direction by alternating current impulses of a single frequency transmitted thereover, and means responsive to the appropriation of said trunk line at one of said offices for rendering said trunk busy at the other said offices until the said means are restored to normal.

5. In a telephone exchange system comprising a first and second office, a two-way interconnecting line between said first and second offices with means for extending a connection in one direction by coded alternating current voice frequency impulses transmitted thereover and for extending a connection in the opposite direction by alternating current impulses of a single frequency transmitted thereover, a first relay device responsive to the appropriation of said trunk line at said first office for controlling further means for extending a connection to said second office, a second relay device responsive to the appropriation of said trunk line at said second office for controlling further means for extending a call in the opposite direction to said first office, means responsive to said first relay device to render said second relay device ineffective to extend a call to said first office, and means responsive to said second relay device to render said first relay device ineffective to extend a call to said second office.

6. In a telephone exchange system comprising a first and second office, a two-way trunk line interconnecting said two offices and terminating in each of them at an operator's position, automatic switches in each of said offices, a plurality of alternating current sources of different frequencies in each of said offices, means in said first office for selectively applying said plurality of alternating current sources over said trunk line to produce a plurality of coded alternating current impulses thereover, means at said second office for selectively applying said plurality of alternating current sources to produce a

- ing device in one of said offices for selectively effecting circuit closure between said sources of alternating current and said line to produce coded alternating current impulses thereover, means controlled by other of said impulsive devices in the other of said offices for effecting a circuit closure between one of said sources of alternating current and said trunk line to produce alternating current impulses of a single frequency thereover, a plurality of tuned alternating current relays, each of said relays being responsive to an alternating current of a particular frequency, a repeating coil at each end of said line, each of said repeating coils having a plurality of primary windings connected in series in said line and shunted by a resistance and a plurality of secondary windings, said secondary windings being in shunt of said line through said alternating current relays to increase the sensitivity of said relays at one end of said line to currents coming from the opposite end of said line and to decrease the sensitivity of said relays at one end of said line to currents coming from the same end of said line, a plurality of direct current relays controlled by said tuned alternating current relays, means controlled by said direct current relays in one of said offices for transmitting a direct current impulse to said register and controlling device when said alternating current relays respond to a coded alternating current impulse, and means controlled by said direct current relays at said other office for producing a direct current impulse to control said automatic switches when one of said tuned alternating current relays responds to one of said alternating current impulses of a single frequency.
10. In a telephone exchange system comprising two offices, an interconnecting two way line between the said offices, automatic switches and register and controlling mechanism at one of said offices and automatic switches at the other of said offices all capable of operable association with the respective end of said trunk line in response to the appropriation of said trunk line for the extension of a call from the other end of said line, an impulsive device in each of said offices capable of being operably associated with each end of said line, sources of alternating current of different frequencies at each of said offices, means controlled by said impulsive device in one of said offices for selectively effecting the circuit closure between said sources of alternating current and said line to produce coded alternating current impulses thereover, means controlled by said other impulsive device in the other of said offices for effecting a circuit closure between one of said sources of alternating current and said trunk line to produce alternating current impulses of a single frequency thereover, a plurality of tuned alternating current relays, each of said relays being responsive to an alternating current of a particular frequency, a repeating coil at each end of said line, each of said repeating coils having a plurality of primary windings connected in series in said line and shunted by a resistance and a plurality of secondary windings, said secondary windings being in shunt of said line through said alternating current relays to increase the sensitivity of said relays at one end of said line to currents coming from the opposite end of said line and to decrease the sensitivity of said relays at one end of said line to currents coming from the same end of said line, a plurality of direct current relays controlled by said tuned alternating current relays, means controlled by said direct current relays in one of said offices for transmitting a direct current impulse to said register and controlling device when said alternating current relays respond to a coded alternating current impulse, and means controlled by said direct current relays at said other office for producing a direct current impulse to control said automatic switches when one of said tuned alternating current relays responds to one of said alternating current impulses of a single frequency.
11. In a telephone exchange system comprising a first office and a second office, a two way trunk line extending between said offices, means including a cord circuit and automatic switches controlled by a series of coded alternating current voice frequency impulses transmitted over said trunk line for establishing a connection between said two offices in one direction, means including a cord and automatic switches controlled by a series of alternating current impulses of a single voice frequency transmitted over said trunk line for establishing a connection between said two offices in the opposite direction, a supervisory signal in each of said cord circuits, a plurality of sources of alternating current of different frequencies in each of said offices, means for producing code impulses of different frequencies over said trunk line, and means responsive to said code impulses over said line to control said supervisory signal.
12. In a telephone exchange system comprising a first office and a second office, a two way trunk line extending between said offices, means including a cord circuit and automatic switches controlled by a series of coded alternating current voice frequency impulses transmitted over said trunk line for establishing a connection between said two offices in one direction, means including a cord circuit and automatic switches controlled by a series of alternating current impulses of a single voice frequency transmitted over said trunk line for establishing a connection between said two offices in the opposite direction, a supervisory signal in each of said cord circuits, a plurality of sources of alter-

nating current of different frequencies operably associable with said trunk line at each end thereof, means for producing coded impulses of different frequencies at each end 5 of said trunk line depending upon the direction of the connection, each of said impulses being composed of a different voice frequency current combinations according to the condition which said impulse is to indicate, alternating current devices at each end of said 10 trunk line responsive to said impulses and means at each end of said trunk line responsive to said alternating current devices for locally operating said supervisory signal 15 in said cord circuit.

13. In a telephone exchange system comprising a first office and a second office, a two-way trunk line extending between said offices, means including a cord circuit and 20 automatic switches controlled by a series of coded alternating current voice frequency impulses transmitted over said trunk line for establishing a connection between said offices in one direction, means including a 25 cord circuit and automatic switches controlled by a series of alternating current impulses of a single frequency transmitted over said trunk line for establishing a connection between said offices in the other direction, a 30 supervisory signal in each of said cord circuits, a plurality of sources of alternating current of different voice frequencies operably 35 associative with said trunk line at each end thereof, means for transmitting impulses of different frequencies in either direction over said trunk line depending upon the direction of a connection, each of said impulses being composed of different voice frequency current combinations according to the condition 40 which said impulse is to indicate, a plurality of tuned alternating current relays at each end of said line responsive to said impulses, and a plurality of direct current relays at each end of said trunk line responsive 45 to the operation of said tuned alternating current relays for locally operating said supervisory signal in said cord circuit.

14. A telephone exchange system comprising a first office and a second office, a two-way interconnecting trunk line extending between said offices, means including a cord circuit and automatic switches controlled by a series of alternating current voice frequency impulses of a single frequency transmitted 55 over said line for establishing a connection between said offices in one direction, means including a cord circuit and automatic switches, and a register and controlling mechanism, said automatic switches and said controlling mechanism being controlled by a plurality of coded alternating current voice frequency impulses transmitted over said line, for establishing a connection between said offices in the opposite direction, a supervisory signal in each of said cord circuits,

a plurality of alternating current sources of different voice frequencies operably associative with said trunk line at each end thereof, means for transmitting coded impulses of different frequencies over said trunk line in either direction, means responsive to the connection of said cord circuit to said trunk line at said first office for extending said trunk line to said register and controlling mechanism at said second office, and means responsive to the connection of said trunk line to said register and recording mechanism for transmitting a coded alternating current impulse to the originating end of said line for operating said supervisory signal in the cord circuit.

15. In a telephone exchange system comprising a first office and a second office, a two-way trunk line extending between said offices, a called line in each of said offices, means including a cord circuit and automatic switches controlled by a series of coded alternating current voice frequency impulses transmitted over said trunk line for establishing a connection between said offices in one direction, means including a cord circuit and automatic switches controlled by a series of alternating current impulses of a single frequency transmitted over said trunk line for establishing a connection between said offices in the opposite direction, a supervisory signal in each of said cord circuits, a plurality of sources of alternating current of different frequencies operably associated with said trunk line at each end thereof, a relay device at each end of said trunk line responsive to each distinct condition of said trunk line, said automatic switches and said called line when interconnected for the extension of a connection from one office to said called line in the other office in the appropriate direction, and means controlled by said relay device for transmitting to the originating end of said trunk line an alternating current impulse of a frequency combination corresponding to any one of said distinct conditions of said trunk line, said automatic switches and said called line at the terminating end.

16. In a telephone exchange system comprising a first office and a second office, a two-way trunk line extending between said offices, a called line in each of said offices, means including a cord circuit and automatic switches controlled by a series of coded alternating current voice frequency impulses transmitted over said trunk line for establishing a connection between said offices in one direction, means including a cord circuit and automatic switches controlled by a series of alternating current impulses of a single frequency transmitted over said trunk line for establishing a connection between said offices in the opposite direction, a supervisory signal in each of said cord circuits, a plurality of

- sources of alternating current of different frequencies operably associative with said trunk line at each end thereof, a relay device at each end of said trunk responsive to each distinct condition of said trunk, said automatic switches and said called line when interconnected for the extension of a connection from one office to said called line in other office in the appropriate direction, a relay, the circuit of said relay being prepared by said relay device when operated, and means controlled by said relay when operated and said relay device when released for transmitting to the originating end of said trunk an alternating current impulse of a frequency combination corresponding to any one of said distinct conditions of said trunk, said automatic switches and said called line at the terminating end.
17. In a telephone exchange system comprising a first office and a second office, a two-way trunk line extending between said offices, a called line in each of said offices, means including a cord circuit and automatic switches controlled by a series of coded alternating current voice frequency impulses transmitted over said trunk line for establishing a connection between said two offices in one direction, means including a cord circuit and automatic switches controlled by a series of alternating current impulses of a single voice frequency transmitted over said trunk line for establishing a connection between said offices in the opposite direction, a supervisory signal in each of said cord circuits, a plurality of sources of alternating currents of different frequencies operably associative with said trunk at each end thereof, a relay device at each end of said trunk responsive to a plurality of distinct conditions of said trunk, said automatic switches and said called line when interconnected for the extension of a connection from one office to said called line in other office in the appropriate direction, a slow release relay responsive to the release of said relay device, a first relay and a second relay, the circuit of said first and second relays being controlled through the contacts of said slow release relay, means controlled by said first relay when operated for transmitting to the originating end of said trunk line an alternating current impulse of a frequency combination corresponding to one of said distinct conditions of said trunk, said automatic switches and said called line at the terminating end, and means controlled by said second relay when operated for transmitting to the originating end of said line an alternating current impulse of a different frequency combination corresponding to one of said distinct conditions of said trunk, said automatic switches and said called line at said terminating end.
18. In a telephone exchange system comprising a first and second office, a two-way interconnecting trunk line between said offices terminating in each of them at an operator's position, automatic switches in each of said offices, an impulsing device, a key and cord circuit at each of said operator's positions capable of operable association with said trunk line when said cord is connected to said trunk line, a relay at each end of said trunk, said automatic switches in each of said offices extending to contacts of each of said relays and means responsive to the operation of said key at one of said positions at one end of said trunk, for operating said relay at the distant end of said trunk for completing an impulsing circuit over said impulsing device, said trunk and said automatic switches at said distant end.
19. In a telephone exchange system comprising a first and second office, a two-way interconnecting line between said offices and terminating in each of them at an operator's position, automatic switches in each of said offices of

offices, an impulsing device, a key and cord circuit at each of said operator's positions capable of operable association with said trunk when said cord is connected to said trunk, a relay at each end of said trunk, said automatic switches in each of said offices extending to contacts of each of said relays, means responsive to the operation of said key at one of said positions for operating said relay at said distant end of said trunk for completing an impulsing circuit over said impulsing device, said trunk and said automatic switches at said distant end, means responsive to operation of said impulsing device for producing a series of impulses over said trunk line and a relay device at each end of said trunk responsive to the termination of said series of impulses for removing said impulsing device from said trunk line.

21. In a telephone exchange comprising a first and second office, a two-way trunk line interconnecting said offices, a plurality of alternating current sources of different frequencies in each of said offices, means in said first office for selectively applying said plurality of alternating currents to said trunk line to produce impulses thereover, means in said second office for selectively applying said plurality of alternating current sources over said trunk line to produce coded impulses thereover, means at said second office for applying one of said plurality of alternating current sources over said trunk line to produce alternating current impulses of a single frequency thereover, means responsive to the appropriation of said trunk line at said first office for setting up a connection at said second office by the said coded alternating current impulses transmitted over said line, means responsive to the appropriation of said trunk line at said second office for setting up a connection at said first office by the said alternating current impulses of a single frequency transmitted over said line, means for

45 selectively applying other coded impulses in either direction for the transmission of supervisory signals, and means provided at both ends of said line for preventing the transmission of signals in one direction over said line during the time that signals are in transit in the opposite direction.

22. In a telephone exchange system comprising a first and a second office, a two-way trunk line interconnecting said offices, a plurality of alternating current sources of different frequencies in each of said offices, means in said first office for selectively applying said plurality of alternating currents over said trunk line to produce impulses thereover, means in said second office for selectively applying said plurality of alternating current sources over said trunk line to produce coded impulses thereover, means at said second office for applying one of said plurality of alternating current sources over said

trunk line to produce alternating current impulses of a single frequency thereover, means responsive to the appropriation of said trunk line at said first office for setting up a connection at said second office by the said coded alternating current impulses transmitted over said line, means responsive to the appropriation of said trunk line at said second office for setting up a connection at said first office by the said alternating current impulses of a single frequency transmitted over said line, means for selectively applying other coded impulses in either direction for the transmission of supervisory signals, a relay device at both ends of said trunk line, and means responsive to the transmission of signals in one direction for operating said relay device at said office where said signal originates for preventing the transmission of signals over said line in the opposite direction.

In witness whereof, I hereunto subscribe my name.

THOMAS SAMUEL SKILLMAN.
